PLUG RECEPTACLE

Christopher I. Smith, New York, N. Y., assignor to
 Marks Products Co., Inc., Brooklyn, N. Y., a
 corporation of New York

Application March 11, 1935, Serial No. 10,384

7 Claims. (Cl. 173—330)

This invention relates to plug receptacles for convenience wall outlets and particularly to that type of such receptacles which are suitable for mounting in an outlet box attached thereto by means of a plate to which said receptacle is fastened.

It is a particular object of the present invention to provide a receptacle of compact design and special construction for use in connection with wall plates and gang boxes.

It is another object of the invention to provide a receptacle of this type having end terminals in order to permit it to be mounted in an outlet box and a plurality of such receptacles to be mounted side by side in a single box as well as in a multiple gang box.

It is a further object of this invention to provide a fully closed receptacle having a body of a single piece of insulating material covered by a plate of similar material.

With these and other objects in view the invention provides a receptacle which is extremely simple in construction, easy to manufacture at a very reasonable price and which facilitates its assembly into gangs with other wiring devices.

The invention will be better understood from the description to follow taken in connection with the accompanying drawing in which—

Fig. 1 is a front elevation of the improved receptacle.

Fig. 2 is a side elevation of Fig. 1.

Fig. 3 is a rear elevation of an open receptacle shown in Figs. 1 and 2.

Fig. 4 is a sectional elevation on line 4—4 of Fig. 1.

Fig. 5 is an end elevation of Fig. 3 from the right.

Fig. 6 is a perspective detail of a contact member.

Fig. 7 is a perspective view showing the receptacle assembled on a wall plate partly in section.

Referring to the drawing, 10 represents a casing of insulating material, preferably of molded phenolic compound. This casing consists of parallel side plates 101 and end plates 102 comprising a rectangle as shown in Fig. 3 and closed by front plate 103 to form a casing open at its rear. The central part of the casing is occupied by a post 104 integral with plate 103 and extending through the casing with end-face spaced a short distance from the rear face of the casing formed by plates 101 and 102 and parallel thereto. Between the two end plates 102 and on opposite sides of post 104 extend two flat brace bars 107 from each end plate perpendicular

thereto to opposite sides of post 10. These bars have their rear faces on a plane with that of post 104 and their front faces about midway of end plates 101. Each bar 107 has a slot 108 formed therein by an offset at the face of one of the plates 101. A similar slot 110 is formed by a ledge 111 at diagonally opposite corners of side plate 101 (see Fig. 3). At the same corners of the casing, rectangular openings 112 are provided in end plates 102 which extend from the rear end of these plates towards the front thereof.

On the outside of the end plates, tubular bosses 113 are provided which extend from the front face of plate 103 rearwardly beyond the middle of plates 102. From the front face of plate 103 projects a short octagon portion 114 and from the face thereof a rectangular portion 115. This rectangular portion is centrally subdivided into two smaller rectangles 116 each provided with a slot 117 located adjacent to opposite sides of post 104. Slots 117 extend only through the portion 114 of the front plates, the other portion of the front openings being hopper shaped. Each of the two hoppers has curved inclined faces sloping towards slots 117. Within this above described casing of a single piece of insulating material are accommodated two contact and terminal supports 120 shown in Fig. 6. They consist of a short rectangular metallic bar 120 provided with a terminal screw 121 having its head on the outside thereof and an angularly bent flat contact spring 122 riveted thereto on the inside and extending perpendicularly from support 120 to one side thereof. Terminal support 120 is inserted into casing 10 from the rear by sliding its ends into slots 108 and 110 whereby the heads of terminal screws 121 come into openings 112 of end plates 102 and the free ends of springs 122 lean against flat sides 118 of part 104. When terminal supports 120 are assembled in casing 10 a closure plate 123 is placed into the rear opening formed by side plates 101 and end plates 102. This plate leans against the rear faces of post 104, bars 107 and terminal supports 120. It is fastened to the casing by a central screw 124 threaded into post 104.

Fig. 7 shows the above described receptacle assembled on a wall plate 125 provided with an opening 119 into which fits the rectangular front portion 115 of the receptacle and the two opposite sides of the octagon portion 114 which are a continuation of the short sides of the rectangular part fit against the sides of ribs 126 of the wall plate while front plate 103 leans against 55

the face of these ribs. Screws 127 pass through tubular bosses 113 into threaded apertures 128 of the ribs 126 and hold the receptacle 10 tightly fastened in proper alignment on wall plate 125.

5 The plug receptacle thus described is specially adapted for use in connection with a wall plate which is described in a copending application for patent filed by me. It is explained in that application how the particular form of the front 10 of this receptacle cooperates with means on the wall plate to align it thereon directly without the use of intermediate aligning means. In addition thereto, the special combination of elements in their relative positions produces an extremely 15 small and compact plug receptacle of the box type which not only may be mounted on a bridge plate for connection to a wall plate and outlet box but which permits the mounting of a plurality of such receptacles on the same wall plate 20 and in the same outlet box of standard size.

While this device has been illustrated in only one form it is adaptable to many modifications in its details of construction, in view of which it is to be understood that the claims are to be 25 construed and the invention is to be limited only by the scope of the claims and not by the illustrated embodiment.

I claim:

1. In a device of the kind described, the combination of a substantially rectangular box-like 30 casing having relatively thin side walls, end walls and a front wall, a central post integral with said front wall, a division wall extending from each end wall to the central post, said walls being offset with respect to each other, terminal supports 35 adjacent and parallel to each end wall each extending from one division wall to one side wall intersecting the plane of the second division wall and having a terminal within an aperture of 40 the adjacent end plate.

2. In a device of the kind described in combination a substantially rectangular casing having parallel side walls and end walls, a front wall integral with said other walls having a central post 45 thereon, a pair of parallel division walls joining said end walls to each other and to said post forming two outer compartments along said side walls and two inner compartments between said post and end walls, a slot formed in each division 50 wall at opposite end walls parallel thereto, a second slot formed in each side wall in alignment with said first slot and a contact support slidably mounted in said slots.

3. In a device of the kind described, a casing 55 rectangular in plan having pairs of parallel enclosing walls integral with each other, a perforated face plate adapted to receive a pair of connection plug prongs therethrough, a central post extending from said face plate into said casing,

a pair of division walls spaced from said face plate joining said post to one pair of opposite sidewalls of said casing dividing said casing into two central and two outer compartments along the second pair of side walls, a contact support extending from each inner compartment into one of the outer compartments holding a contact spring in said inner compartment and a terminal in said outer compartment.

4. In a device of the kind described, a casing 10 rectangular in plan having pairs of parallel enclosing plates integral with each other, a perforated face plate adapted to receive a pair of connection plug prongs therethrough, a central post 15 extending from said face plate into said casing, a pair of brace bars spaced from said face plate joining said post to one pair of opposite sides of said casing and dividing said casing into two central and two outer compartments along the second pair of parallel plates, a contact spring 20 in each central compartment and a terminal in each outer compartment adjacent diagonally opposite corners of said casing.

5. In a device of the kind described, a casing 25 having a front plate and relatively thin enclosing walls adapted for attachment in multiple to a single gang wall plate, a plurality of parallel interior compartments in said casing all having full size openings through the rear of said casing, one pair of said compartments enclosing contact 30 members and another pair accommodating terminal connectors at diagonally opposite corners of said casing.

6. In a device of the kind described, a casing 35 having a front plate, a central post, and relatively thin enclosing walls forming a hollow rectangle adapted for attachment to a wall plate, a pair of parallel division walls connecting opposite outside walls and said post forming two pairs of compartments in said casing, one pair of said 40 compartments enclosing contact members and another pair accommodating terminal connectors at diagonally opposite corners of said casing.

7. In a device of the kind described, a box-like 45 casing having a face plate and enclosing wall plates integral with each other and with said face plate, a post on said face plate for mounting a rear plate, a pair of division walls joining one pair of opposite end walls to each other and to said post forming three compartments along each 50 one of the end walls joined to said post, a contact spring in each middle compartment, terminal screws in diagonally opposite spaces of the outer compartments and a pair of terminal straps each holding one of said contact springs and one of said terminal screws and guides formed on said division walls to align said terminal straps on the inner face of said joined sides of the casing.

CHRISTOPHER L. SMITH.
